OTHER PUBLICATIONS

U.S. Appl. No. 61/916,593, filed Dec. 16, 2013, titled "Container for Disposable Spray Gun Components".

Primary Examiner — Robert M Spear*Assistant Examiner* — Marissa J Cash(74) *Attorney, Agent, or Firm* — Aleksander Medved(57) **CLAIM**

The ornamental design for a container for disposable spray gun components, as shown and described.

DESCRIPTION

FIG. 1 is a perspective view of a container for disposable spray gun components embodying the new design;

FIG. 2 is a front view of a container for disposable spray gun components embodying the new design;

FIG. 3 is a rear view of a container for disposable spray gun components embodying the new design;

FIG. 4 is a left side view of a container for disposable spray gun components embodying the new design (the right side view is a mirror image of the left side view and therefore is not shown);

FIG. 5 is a top view of a container for disposable spray gun components embodying the new design; and,

FIG. 6 is a bottom view of a container for disposable spray gun components embodying the new design.

The broken line showing forms no part of the claimed design.
